UNITED STATES PATENT OFFICE.

GEORGE A. CLEMENT, OF MOUNT VERNON, NEW YORK, ASSIGNOR TO DUALUXE COMPANY, INC., A CORPORATION OF DELAWARE.

FUSING CLIP FOR BIFOCAL LENSES.

Application filed August 13, 1925. Serial No. 50,084.

My invention relates to means for properly holding the parts of fused bifocal lens blanks during the fusing operation. Such blanks are ordinarily made by fusing a button or segment of flint glass on to a seat prepared in the surface of a major lens blank consisting of a block or disc of crown glass, and the finished lens is thereafter formed from the blank, the face in which the 5 segment is fused being ground and polished down to a smooth surface of continuous curvature, and the other side being shaped according to prescription. The area which includes the segment constitutes the stronger 10 or reading lens portion of the bifocal lens.

In the manufacture of such blanks, the seat for the button or segment is prepared on the major lens by grinding and polishing a portion of one surface of the major lens to 20 the desired curvature, and the flint glass button which is to be fused on this seat has its contact surface also properly ground and polished. Since the flint glass has a lower fusing point than the crown glass it will 25 drop down and adapt itself to the shape of the seat. In order to extrude all air and gases from between the contact surfaces as the fusing proceeds, means are employed to hold the button in a tilted position on its 30 seat so that when placed in the furnace it contacts at or near its outer edges. As it softens and drops down therefore under the action of the heat, it will gradually sink from the original point of contact and progressively and outwardly enlarge its area of 35 contact, and, in that way, avoid the entrapping of the air and gases formed during the fusing operation.

It is important to prevent the button from 40 shifting on its seat after it has been finally placed preparatory to fusing, and it is desirable that any holding means employed for this purpose should be able to adapt itself to the relative positions of the seat on the 45 surface of the major lens blank, and also to various sizes of blanks.

In accordance with my invention, I employ a fusing block of refractory material upon which the major lens blank is placed 50 with the seat prepared usually at one edge thereof, and I provide an arched-shaped stop member adjustably carried by the block so that it can be brought across the seat and properly position the button thereon. This

segment-positioning or stop member may 55 conveniently be part of a wire bowed spring clip, the ends of which bear frictionally against the sides of the block and the center of which is bent up to form the segment-positioning portion. Cooperative with this positioning member is a pressure device which bears on the top of the segment between the uprights of the arched portion and tilts the segment on its seat. 60

I shall now describe the illustrated embodiment of my invention and shall thereafter point out my invention in claims. 65

Fig. 1 is a plan view of a suitable segment-positioning member.

Fig. 2 is a side elevation of the same. 70

Fig. 3 is a side elevation of one form of pressure device for tilting the segment.

Figs. 4 and 5 are, respectively, a side elevation and plan of a complete assembly embodying my invention as used with a wide 75 angle segment.

Figs. 6 and 7 are corresponding views of an assembly as used with a round segment.

The fusing block 1 of carborundum or other suitable material is thicker at one 80 edge than at the other so that its top surface is inclined, although it will be understood that this surface configuration of the block is not an essential part of my invention. The major blank 2 which is supported 85 on this block is shown as concavo-convex in form and the top surface of the block 1 is correspondingly convexed. If desired, a

stop may be provided on each of the lower corners of the block to facilitate the positioning of the major blank thereon, but such stops, while convenient, are not necessary and are therefore not shown. The seat 3 for the segment 4 is formed on the convex side of the major lens blank, a segmental 90 portion being finished off from the edge to near the center of the blank. The buttons are shown as more nearly plano, since the seat 3 is shown as a convex spherical or plus surface, and the buttons have their under 95

surfaces ground and polished so as to properly fuse with the surface of the seat as the button drops down to the conformation of the seat. 100

To properly position the button on its seat, 105 a stop member is employed of the character shown in Figs. 1 and 2. This is a bowed spring wire member of substantially bail

shape or U-shape, the two arms 5 and 6 terminating in looped ends, and the intermediate or cross part having its middle portion bent or arched up to form a segment-positioning member 7. This arch 7 which has a spread somewhat less than the diameter of the button, makes an obtuse angle with the arms 5 and 6, and the top part of the arch is bent inwardly to an angle with its apex toward the looped ends, for the purpose of providing clearance for the pressure device, as will presently appear. The two arms 5 and 6 are spaced to grip the sides of the block 1, and the height of the portion 7 is substantially greater than the combined thickness of the major lens blank and of the segment.

The major lens blank 2 is shown as placed on the block 1 with the seat for the segment disposed at the higher side. The seat is thereby substantially horizontal. The wire stop member is placed upon the block with the two arms frictionally gripping the sides of the block which grip is augmented by the looped ends, and it is adjusted on the block so that the intermediate portion crosses over the higher side of the face of the major lens blank. This brings the arched portion 7 over the outer edge of the seat, and the segment is then placed on the seat against the uprights of the arch, and is in that way properly positioned on its seat. When the wide angle segment 4 is used, the stop member rests upon the block 1, as shown in Figs. 4 and 5. When a round segment 4^a is used, the stop member is placed upon the major lens blank, as shown in Figs. 6 and 7, since the round segment is smaller and will project farther through the arched portion of the segment. The adjustability of the stop member on the block permits of this alternative disposition of the segment-positioning arch 7.

In order to tilt the segment on its seat a pressure device is used, such, for example, as shown in detail in Fig. 3. In the illustrated form this consists of a hook-shaped, wire spring clip 8, the long arm of which is straight and in the fusing assembly bears in a narrow central longitudinal slot 9 in the bottom of the block 1, while the hooked end bears with its point on top of the segment near its outer edge which may have a slight recess formed to receive the point.

The parts may be quickly assembled with assurance that the two lens parts will be properly related. The whole assembly may then be picked up and moved with the exercise of a little care without displacing the segment. The conventional fusing block requires no substantial change for use in my assembly and there is nothing in the assembly to be injured by the heat.

It is obvious that various modifications may be made in the construction shown in

the drawings and above particularly described within the principle and scope of my invention.

I claim:

1. For fusing bifocal lenses composed of a major lens and a segment fused on a seat formed in the surface of the major lens, means for holding the parts while fusing comprising a supporting block for the major lens, and a U-shaped segment-positioning member adapted to span the block with its intermediate portion and frictionally engage the sides of the block with its ends and having its middle portion upwardly arched for a width less than that of a segment. 80

2. For fusing bifocal lenses composed of a major lens and a segment fused on a seat formed in the surface of the major lens, means for holding the parts while fusing comprising a supporting block for the major lens, and a resilient wire segment-positioning member of U-shape adapted to span the block with its intermediate portion and frictionally engage the sides of the block with its ends and having its middle portion upwardly arched for a width less than that of a segment. 90

3. For fusing bifocal lenses composed of a major lens and a segment fused on a seat formed in the surface of the major lens, means for holding the parts while fusing comprising a supporting block for the major lens, a U-shaped segment-positioning member adapted to span the block with its intermediate portion and frictionally engage the sides of the block with its ends and having its middle portion upwardly arched for a width less than that of a segment, and a pressure device adapted to bear on the top of a segment positioned within the said arched portion and tilt the same on its seat. 100

4. For fusing bifocal lenses composed of a major lens and a segment fused on a seat formed in the surface of the major lens, means for holding the parts while fusing comprising a supporting block for the major lens, a U-shaped segment-positioning member adapted to span the block with its intermediate portion and frictionally engage the sides of the block with its ends and having its middle portion upwardly arched for a width less than that of a segment, and a hook-shaped spring clip adapted to bear on the underside of the block with one end and having a downwardly directed point on the other end adapted to bear on the top of a segment near its outer edge within the said arched portion and tilt the same on its seat. 110

5. For fusing bifocal lenses composed of a major lens and a segment fused on a seat formed in the surface of the major lens, means for holding the parts while fusing comprising a supporting block for the

major lens, a resilient wire segment-positioning member of U-shape adapted to span the block with its intermediate portion and frictionally engage the sides of the block with its ends and having its middle portion upwardly arched for a width less than that of a segment, and having the cross-piece of the arch bent inwardly, and a hook-shaped spring clip adapted to bear on the top of a segment positioned within the said arched portion and tilt the same on its seat.

6. For fusing bifocal lenses composed of a major lens and a segment fused on a seat formed in the surface of the major lens, 15 means for holding the parts while fusing comprising a supporting block for the major lens, and an arch-shaped segment-positioning member adjustably carried by the block and arranged to rest upon the top of the 20 block near one edge thereof.

In witness whereof, I hereunto subscribe my signature.

GEORGE A. CLEMENT.
